Kennebunk, Maine

Application May 15, 1957, Serial No. 659,341

1 Claim. (Cl. 36—68)

This invention relates to counters for shoes and has for its principal object to provide a counter which may initially be molded to fit snugly about the heel portion of the foot and yet will be sufficiently flexible along its upper margin to yield readily to the heel during walking and hence to minimize chafing or discomfort. Another object is to provide a counter which will have a flexible top to afford comfort, and firm sidewalls which will hold their shape and hug the foot. Another object is to provide a counter with a flexible top for comfort which will still have enough strength and body to be molded and to retain its molded shape. Another object is to provide a counter which will yield readily at its upper margin but will become increasingly resistant to yielding in proportion to the degree of outward flexing so that it will not gape. Another object is to provide a counter which will shrink to the inside as it dries so as to compensate for swelling due to moisture introduced during processing or from perspiration when the shoe is worn.

As herein illustrated the counter has upper and lower portions characterized in that the upper portion contains a plurality of uniformly spaced, elongated slits which extend part way but not all the way through from the side of the counter which will be the outside when the latter is disposed in the shoe toward the inside and wherein the slits are arranged in spaced parallel rows paralleling the lower edge of the counter, which run around the counter from one end to the other, and that the lower portion is devoid of slits. The slits in adjacent rows are staggered and the unslotted portions between adjacent ends of the slits are correspondingly staggered and constitute discontinuous hinges which afford a maximum of flexibility without loss of strength so that molding may be attained with greater uniformity and fidelity than would otherwise be possible. Preferably the spacing between slits and between lines of slits is proportioned so that the unslotted diagonals heightwise of the counter between any adjacent rows of slits heightwise of the counter is in the order of 30° to the lower edge of the counter. Each slit is wedge-shaped so that flexing toward the inside meets less resistance than flexing toward the outside and is adapted to take up and retain adhesive applied thereto when assembled during shoe making which will impart permanent flexibility thereto.

The invention will now be described in greater detail with reference to the accompanying drawings wherein:

Fig. 1 is a plan view of the counter in the flat prior to molding;

Fig. 2 is an enlarged section taken on the line 2—2 of Fig. 1;

Fig. 3 is a perspective view of the counter after molding;

Fig. 4 is a section taken on the line 4—4 of Fig. 3, to much larger scale, showing the margin in its normal position in full lines and opened up in dot and dash lines;

Fig. 5 is an enlarged fragmentary section of the counter showing the normal shape of a single slit filled with

2

an adhesive as it would be when incorporated in the shoe, the adjacent parts of the shoe being omitted;

Fig. 6 is a corresponding section of the counter showing the shape of a single slit when, for example, the 5 counter portion has been distended as illustrated in the dot and dash lines in Fig. 4; and

Fig. 7 is a vertical section through the counter portion of a shoe showing the counter assembled between an upper and lining.

10 Referring to the drawings, the counter 10 is shown as a flat blank, prior to molding, which is cut out of a suitable material such as a flexible fiberboard, it being understood however that any material susceptible of molding and retaining its shape so as to provide the desired stiffness and permanence to the back part of the shoe may be employed.

The blank has a relatively stiff body or sidewall portion 12 and a flexible margin or top portion 14. Flexibility is imparted to the top portion, as herein 15 shown, by skiving that portion to provide a wide thin scarf on the side 16 which in the molded counter will be the inner side of the counter. The scarf extends from approximately the line a—a (Fig. 1), upwardly to its top edge. Although the scarf is illustrated as being on the inner side it is to be understood that it may be on the outer side if desired. The top portion is made flexible by cutting into the outer side 18 a plurality of uniformly spaced slits 22 arranged in spaced parallel lines 20, the lines and slits paralleling the line a—a. The 25 slits 22 in adjacent rows are staggered so that a slit in one row lies laterally of and between the adjacent ends of a pair of adjacent slits in the next row. The distance between rows is approximately one-half the length of a slit. As thus proportioned the diagonals between 30 the adjacent rows of slits heightwise of the counter are in the order of 30° to the bottom line of the counter. The spaces between adjacent lines and between adjacent slits constitute a plurality of hinges 23 which are likewise 35 staggered and because of their discontinuity allow the 40 substance of the counter to be bent readily and to take the shape required easily and with a fidelity that otherwise would be unattainable without loss of strength.

The slits 22 moreover are cut or impressed in the outer surface 18 so as to extend from the outer surface inwardly almost to but not clear through the inner surface. This allows the top portion to be bent inwardly much more readily than outwardly and hence to be bent to lie close to the foot in the narrow area above the heel and between the ankle bone. As pointed out the 45 slits do not extend all the way through to the inner side of the counter and the unslotted layer which lies inside of the inner extremities of the slits resists bending of the counter to the outside and hence gaping of the counter at the top. This unbroken inner surface also tends to 50 shrink to a greater extent than the broken outer surface so as to promote a drawing inwardly of the counter walls as they dry. Resistance to outward bending increases with opening of the counter due to the resistance of the wedge-shaped slits (Figs. 5 and 6) to closing and thus 55 further helps to prevent gaping. Preferably the cuts are made so as to be right triangular with the right angle base of the triangle at the lower outer side with respect to the top and bottom edges of the counter.

The slits are made by subjecting the counter blank 60 while flat to a gang of spaced disk-like cutters which have chisel-shaped cutting teeth suitably spaced about their periphery and staggered in adjacent disks so that when the blank supported by a bed plate is passed beneath the gang cuts of the kind described and shown in Figs. 1 to 6 65 inclusive, will be made in the flat blank substantially parallel to its lower edge. Suitable adjustments are, of course, provided for the gang for varying the depth of 70

the slits and for taking care of different thickness of counter material.

After the blank has been subjected to the slitting operation it is molded to impart to it the shape shown in Fig. 3, in which the back part is cupped to snugly engage the heel tendon, that is, the narrow area above the heel and below the ankle bone and the forwardly extending wings or quarter portions are inwardly concaved so that the upper edges along the sidewalls closely embrace the sides of the heel. An inturned lasting flange is simultaneously formed along the lower edge. The V-shaped slits in the outer surface of the counter provide pockets 22 in the surface which will take up and hold an appreciable quantity of adhesive so that when assembled with the upper in the manufacture of the shoe there will be a sufficient quantity of adhesive available to make a permanent bond between the counter and the outer material, that is, the upper. Thus in a finished shoe, a fragmentary portion of which is shown in Fig. 7, the counter is pocketed between the upper material 26 and the lining 28 and is bonded to the upper by a body of adhesive, a portion of which covers the outer surface of the counter and other portions of which occupy the open slits. An adhesive is employed which when set up is characterized in that it is elastic and flexible so that the counter retains its flexibility in the shoe and so that in addition the elasticity of the adhesive cushions outward distortion of the counter and tends to cause it to spring back, that is, inwardly toward its originally molded shape. By way of example, a latex base adhesive is used such as BB Chemical Company's No. 1816.

As thus constructed the top portion 14 of the counter is made permanently and elastically flexible so that while it will open outwardly, as shown in Fig. 4, from its normally closed position, for example, when thrusting the foot into the shoe so as to admit the foot easily it will immediately return to its closed position snugly to engage the sides of the foot when the latter is thrust into place. This eliminates and makes it unnecessary for the retail shoe salesman to break the counter down by distortion and/or otherwise abusing it and also minimizes gaping during walking.

By providing the slits on the outer surface rather than on the inner surface as has been done before the resistance to outward flexing increases with the degree of flexing hence gaping and/or permanent opening is minimized. Opening is also lessened to some extent by the presence of adhesive in the slits which acts as a yielding cushion, allowing the top to open but elastically restoring the top to its closed position.

It should be understood that the present disclosure is for the purpose of illustration only and that this invention includes all modifications and equivalents which fall within the scope of the appended claim.

We claim:

10 The combination with a shoe upper, of a generally U-shaped fiber counter, disposed about the back part thereof, said counter having relatively stiff lower part and a relatively flexible thinner upper part, said thinner upper part containing in its outer side a plurality of spaced open pockets arranged in rows lengthwise of the counter, the pockets in each row being V-shaped and disposed end to end with their apices lengthwise of the counter and spaced from the inner side, leaving a substantially unbroken inner layer between the bottoms of the pockets and the inner side, the converging top and bottom sides of the pockets being substantially symmetrical with respect to the apices, and a body of elastic and flexible adhesive bonding the outer side of the counter to the upper, said adhesive extending into each pocket and separating the converging walls of the pocket from each other.
